REEL FOR MOTION-PICTURE FILMS

Trevor Faulkner and Ralph D. Whitmore,
New York, N. Y.

Application May 7, 1947, Serial No. 746,448

9 Claims. (Cl. 242—70)

1

This invention relates to reels and more particularly to reels for motion picture films.

At the present time, in order to remove a film from a motion picture reel of the usual construction, for whatever purpose, it is necessary to unwind or uncoil the film from the reel. This is obviously time consuming and when many films are handled the expense involved is very considerable.

This invention has for its salient object to provide a reel for motion picture film so constructed and arranged that the film can be easily and quickly removed from the reel without unwinding.

Another object of the invention is to provide a motion picture film reel so constructed that one or both of the side plates of the reel can be removed.

Another object of the invention is to provide a motion picture film reel that is rugged and strong in construction and has removable side plates and releasable means for latching the plates in position.

Further objects of the invention will appear from the following specification taken in connection with the drawings which form a part of this application, and in which

Fig. 1 is a side elevation of a reel constructed in accordance with the invention;

Fig. 2 is a sectional elevation of the reel shown in Fig. 1;

Fig. 3 is an enlarged view, partly broken away and partly in section, illustrating the means for attaching one of the side plates to the central supporting disk;

Fig. 4 is a sectional elevation showing one side plate mounted in operative position on the central supporting disk and the other side plate detached therefrom;

Fig. 5 is a sectional elevation taken substantially on line 5—5 of Fig. 3, looking in the direction of the arrows; and

Fig. 6 is a sectional elevation taken substantially on line 6—6 of Fig. 3, looking in the direction of the arrows.

The embodiment of the invention illustrated in the drawings comprises essentially four principal parts, namely, a hub 10, central supporting disk 11, and two side plates 12 and 13. The hub 10 consists of a casing comprising two halves or sections 14 and 15 having mounted centrally therein a bearing sleeve 16. The sections 14 and 15 have inturned flanges 17 and 18 which are welded or otherwise secured to the outer ends of the sleeve 16, and these sections also have

2

outturned flanges 19 and 20 which are welded or otherwise secured to the outer surfaces of the disk 11. The disk 11 has a central opening which receives the sleeve 16 and laterally extending flanges or lugs 25 which are welded to the outer surface of the sleeve 16.

The disk 11 has formed thereon at its outer periphery, two sets of latching lugs 26 and 27. These lugs are formed by a plurality of radial slits 28 and a plurality of circumferential slits 29 disposed at the inner ends of the radial slits 28. The lugs 26 and 27 are formed by bending or forcing the material bordering the slits 28 alternately in opposite directions, the lugs 26 being bent in one direction from the plane of the disk and the lugs 27 being bent in the other direction. After being bent away from the plane of the disk, the lugs are bent to a position parallel to the surface or plane of the disk, as shown in Fig. 5.

The side plates have formed therein central openings 30 adapted to fit around the hub 10, the walls of the plates bordering the central opening being offset as shown at 31 to receive the flanges 19 and 20. The outer portions of the side plates 12 and 13 are offset to form reel supporting surfaces 32 and 33 and at the outer ends of these surfaces the side plates extend outwardly to form the sides 34 and 35 of the reel support. It will be understood that the surfaces 32 and 33 are dimensioned to conform substantially to the width of the film to be mounted on the reel.

Each of the side plates has formed therein a series of annularly arranged openings 40 adapted to receive the lugs 26 or 27 and adjacent the openings 40 are formed slightly offset projections 41. In order to secure one of the side plates to the supporting disk 11, the plate is inserted over the hub 10 in such a position that the lugs 26 or 27 will project through the openings 40 and thereafter the plate is rotated to the position shown in Figs. 1, 3 and 5 so that the lugs will be disposed on the opposite side of the supporting disk. The lugs 26 and 27 will also engage the offset projections 41, thus insuring the tight engagement of the side plates with the supporting disk 11.

In order to lock the side plates in operative position, each of the side plates has pivotally mounted thereon, a latching lug. In Fig. 6 the lug is shown as mounted on a pivot 45 and comprises a projection 46, a handle portion 47 on one side of the pivot, and a tail 48 on the other side of the pivot 45. The pivot 45 has a head 49 at its inner end and between the head and the offset

portion 50 of the side plate there is positioned a spring 51 which permits a limited axial movement of the latching member on the pivot 45. The disk 11 has slots 52 formed therein and each of the side plates has a slot 53 which is aligned with a slot 52 when the side plate is in locked position on the supporting disk 11. In order to release the side plate, the handle 47 is lifted or pulled away from the surface of the side plate to release the lug 46 from the slots 52 and 53, whereupon the latch can be rotated on its pivot about the tail 48 as the fulcrum to a position in which the lug 46 will rest against the outer surface of the side plate. The side plate can then be rotated in the required direction to release the lugs 26 or 27 from the openings 40.

It will be evident, therefore, that the side plates can be easily and quickly secured to or removed from the disk 11 and thus the film can be easily removed from the reel in coiled condition or without unwinding. The periphery of the reel and of the disk are slotted, as shown at 55 and 56, to receive the end of the film as it is wound on the reel.

Although one specific embodiment of the invention has been particularly shown and described it will be understood that the invention is capable of modification and that changes in the construction and in the arrangement of the various cooperating parts may be made without departing from the spirit or scope of the invention, as expressed in the following claims.

What we claim is:

1. A reel comprising a central hub, a disk extending outwardly from the periphery of the hub and disposed substantially at the longitudinal center of the hub, offset lugs arranged annularly on said disk, said lugs comprising two sets disposed respectively in offset relation to the opposite surfaces of the disk, and side plates having annular spaced openings dimensioned to receive said lugs and to coat with the lugs in securing the side plates to the opposite surfaces of the disk.

2. A reel comprising a central hub, a disk extending outwardly from the periphery of the hub and disposed substantially at the longitudinal center of the hub, offset lugs arranged annularly on said disk, said lugs comprising two sets disposed respectively in offset relation to the opposite surfaces of the disk, side plates having annular spaced openings dimensioned to receive said lugs and to coat with the lugs in securing the side plates to the opposite surfaces of the disk, and releasable latching means for latching each plate to the disk in locked position thereon.

3. A reel comprising a central hub, a disk extending outwardly from the periphery of the hub and disposed substantially at the longitudinal center of the hub, offset lugs arranged annularly on said disk, said lugs comprising two sets disposed respectively in offset relation to the opposite surfaces of the disk, and side plates having annular spaced openings dimensioned to receive said lugs and to coat with the lugs in securing the side plates to the opposite surfaces of the disk, one set of lugs extending in one direction and the other set extending in the opposite direction.

4. A reel comprising a central hub, a disk extending outwardly from the periphery of the hub and disposed substantially at the longitudinal center of the hub, offset lugs arranged annularly on said disk, said lugs comprising two sets disposed respectively in offset relation to and substantially parallel to the opposite surfaces of

the disk, and side plates having annular spaced openings dimensioned to receive said lugs and to coat with the lugs in securing the side plates to the opposite surfaces of the disk.

5. A reel comprising a central hub, a disk extending outwardly from the periphery of the hub and disposed substantially at the longitudinal center of the hub, offset lugs arranged annularly on said disk, said lugs comprising two sets disposed respectively in offset relation to and substantially parallel to the opposite surfaces of the disk, and side plates having annular spaced openings dimensioned to receive said lugs and to coat with the lugs in securing the side plates to the opposite surfaces of the disk, one set of lugs extending in one direction and the other set extending in the opposite direction.

6. A reel comprising a central hub, a disk extending outwardly from the periphery of the hub and disposed substantially at the longitudinal center of the hub, offset lugs arranged annularly on said disk, said lugs comprising two sets disposed respectively in offset relation to the opposite surfaces of the disk, and a pair of side members, each having a central opening receiving said hub and having an offset cylindrical portion having a width substantially equal to one-half the width of a film to be mounted on the reel, said side members having annular spaced openings dimensioned and located to receive and coat with said lugs in securing the side members to said disk.

7. A reel comprising a central hub, a flat disk extending outwardly from the periphery of the hub and disposed in a plane located substantially at the longitudinal center of the hub, side plates disposed on and engaging the opposite surfaces of said disk and extending outwardly beyond the periphery of the disk, and releasable coating securing means carried by said side plates and disk and including means formed integral with the disk for independently securing the side plates to said disk, said securing means being movable into securing position by the relative rotation of the plates and disk.

8. A reel comprising a central member, identical side plates disposed on and engaging opposite surfaces of and extending outwardly beyond the periphery of said central member, said plates being flanged at their outer peripheries to form reel supporting surfaces, coating securing means carried by said side plates and central member and including means disposed annularly and concentrically with respect to the axial center of the central member for independently releasably securing the side plates to said central member, said securing means being movable into securing position by the relative rotation of the plates and disk, and releasable locking means for locking the side plates in secured position.

9. A reel comprising a central hub, a disk extending outwardly from the periphery of the hub and disposed in a plane located substantially at the longitudinal center of the hub, identical side plates disposed on and engaging the opposite surfaces of and extending outwardly beyond the periphery of said disk, said plates being flanged at their outer peripheries to form reel supporting surfaces, and releasable coating securing means carried by said side plates and disk and including means disposed annularly and concentrically with respect to the hub axis for independently securing the side plates to said disk, said securing means being movable into securing

position by the relative rotation of the plates and disk.
